UNITED STATES PATENT OFFICE.

FREDERICK WILKINSON, OF GLAZENWOOD, NEAR BRAINTREE, ENGLAND.

STAMPING MECHANISM.

1,140,013.

Specification of Letters Patent. Patented May 18, 1915.

Application filed May 11, 1912. Serial No. 696,699.

To all whom it may concern:

Be it known that I, FREDERICK WILKINSON, a subject of His Majesty the King of England, residing at Glazenwood, near 5 Braintree, in the county of Essex, Kingdom of England, have invented certain new and useful Improvements in Stamping Mechanism, of which the following is a specification.

10 This invention relates to improvements in coin-freeed machines of the kind adapted for stamping the impression of an official mark, seal or the like upon letters, post-cards and the like, so that the sender may use such 15 machine which is arranged in connection with a post-box or a receptacle, for effecting prepayment of the usual postal rate in lieu of ordinary adhesive stamps.

It has for one of its objects to provide a 20 more simple and effective machine wherein the die or stamping device is arranged in one of a pair of pressure rolls between which the letter, card or the like is passed and stamped before dropping into the receptacle 25 or letter box.

Another object is to provide such a machine with an improved coin-freeed mechanism which will insure that the feed rolls cannot be turned to take a letter until a coin 30 has been inserted.

I will now describe the preferred manner of carrying out my invention with reference to the accompanying drawings, in which:—

Figure 1 shows a front elevation of a box 35 or casing adapted to serve as a pillar box or receptacle for posted letters, and having my stamping machine fitted on the inside of the door thereof. Fig. 2 is an enlarged elevational view of the machine and the reverse 40 side of the door; Fig. 3 is a side elevation of same; Fig. 4 is a like view, with the side of the bed plate or frame removed; Fig. 5 is a sectional elevation about the line A—A of Fig. 1, and Figs. 6 to 12 are detail views 45 of the coin freed mechanism. In these figures the parts of the coin cylinder and their frame or base are disposed above one another to indicate their respective positions when assembled. Thus, Figs. 6-8 are views, 50 each partly in section, of the frame or base; Fig. 9 is a plan view of the main portion of the coin cylinder; Fig. 10 is an end view of Fig. 9, Fig. 11 shows the smaller portion or half of the cylinder removed from the 55 other portion but of course reversed to show the formation of the inner surface thereof.

Fig. 12 is an end view of Fig. 11. Fig. 13 is a view showing the parts of the coin-cylinder assembled in the frame, and the positions of parts after a coin has been inserted. 60

As shown I provide a pair of rolls or drums *a* *b* the latter of which has the coil spring *c* attached to its spindle for returning parts to the normal position, which rolls are adapted to be rotated from the spindle 65 *d* and the operating handle *e* through the medium of the worm wheel *f* mounted on said spindle, the worm wheel *g* mounted on the spindle of the roll *b*, and the two gear wheels *h*, *i* fixed or formed on the two rolls. 70 The handle *e* is fixed on the disk *k* which rotates in front of the door *l* of the casting *m* which is formed to contain the machine and, if desired, to collect the letters, post-cards and the like when they 75 have been stamped by said machine. The door or front *l* is furnished with suitable face plates *n*, *o* in which the coin slot *p* and the letter opening *q* terminate. A die *r* with a curved or straight surface 80 is mounted in the roll *a* in a diametrical bore therein or therethrough, and it may be arranged that it will normally contact with a spring or resilient bed in the face of the contacting roller *b*. Such a resilient bed may conveniently be formed by arranging a plurality of plungers in the face of the counter roll *b* and these would be normally pressed outwardly by a rubber base piece arranged under said members. 85

A suitable device for inking the die consists of a rubber-covered contact roller *8* and an ink roller *9* mounted in a pivoted frame which is adjustable by means of nuts on the screw-threaded post *10*. 90

The die-carrying roll *a* is preferably provided with a plurality of other dies or marks *s* forming a pattern which would be registered on the surface of the envelop, post-card or the like, thereby enabling the exact 100 position of the die proper to be determined in relation thereto for the purpose of detecting fraud.

The coin freed mechanism shown particularly in Figs. 5 to 13 comprises a rotating two-part cylinder *t*—*t'* geared and moving with the rolls by means of the wheels *u*, *v*—*v*—*v*, and having a coin slot or aperture *w* therein normally adapted to register with the slot *p* in the face plate *n*. Normally before a coin is inserted into the mechanism, the cylinder is held from ro- 105

tation by means of the member α controlled by a light spring α' which member has a projecting portion y adapted to engage teeth or notches z in the bearing ring 1 , at 5 one side of the coin cylinder, should the latter be slightly turned. A coin inserted into the slot w falls by gravity into the slot w of the cylinder, engages between the face t^2 of the part t' of the cylinder and the member 10 α , and presses the latter back as shown in Fig. 13, thus when the handle e is operated the coin engaging with and holding the member α back against its spring prevents the projecting y thereon entering the notches 15 z ; thus the cylinder and the rolls may be rotated.

The coin is ejected from the slot w , upon the rotation of the coin cylinder, by means of the lever 2 , the end 3 of which engages 20 in the cam groove 4 in the frame at one end of the coin cylinder.

The spindle of the coin cylinder is provided with an integrating mechanism 5 for recording the number of operations. In 25 some cases, means may be provided for successively numbering the letters or the like passed through the stamping mechanism, and as the coins are deposited in order in a chute 6 and collector 11 , even if a metal 30 disk or counterfeit coin were inserted the sender could be traced by the number of the letter and the position or order of the coin in the collector.

The means shown for operating the integrating mechanism 5 consists of a disk 12 mounted on one end of the spindle 13 of the coin cylinder and having a cam groove 35 14 in which a pin 15 fixed on the lever 16 travels, the movements of the lever being 40 transmitted to the device 5 by links 17 .

A spring 7 or a weight is provided to assist the return of the coin-cylinder to its initial position after each operation.

If desired the feed or stamping rolls may 45 be arranged over a suitable letter receptacle other than the bottom of the casing m , so that the letters, cards or the like will fall from between said rolls, after they have been stamped, into the receptacle.

50 The door l is provided with suitable direction plates or tablets for the information of the public, the plates 18 giving directions as to the insertion of the letters, post-cards and the like into the slot q and the operation 55 of the handle e , and the plate 19 the coin to be used, and if desired the disk k may also bear directions as to the operation of the handle. If wide letters have to be stamped the hinged flap 21 has to be raised 60 away from the slot q . In the example shown the handle e has to be turned through two complete revolutions for the proper working 65 of the stamping mechanism, and for this purpose the series of rotating and co-acting blocks or segments are provided on

the spindle d to rotate therewith in known manner.

One end of the roll b is furnished with ratchet teeth 22 , and when a letter or the like is passing between the two rolls a slight 70 movement of the roll a upward, against the compression of adjustable springs 23 contained in the cups 24 and bearing upon the sliding bearing blocks 25 , allows the pivoted trip or motion multiplying lever 26 to 75 swing upward by medium of the leaf spring 27 , which lever frees the adjustable screw 28 mounted in an arm on the pivoted pawl 29 and allows the letter to drop into said teeth 22 , thus preventing backward rotation of the rolls, once they have started to rotate, and withdrawal of the letter. The 80 springs 23 and 27 are of such co-acting and opposing strengths that normally the pawl 29 is held just away from the teeth 22 as 85 shown in Fig. 5.

It will be seen from the drawings that the coin collector 11 is detachably attached to the end of the chute 6 by pins and bayonet slots, and the lower end of said collector is preferably provided with means for securing it against tampering and fraudulent removal of the coins, by a padlock or the like, or if desired the coins may be arranged to drop into a box or other form of receptacle under the chute. 90

Now referring to Figs. 5 to 13, it will be seen that the coin cylinder is split into two parts or halves t , t' which are formed and recessed to provide the coin slot w and to 100 contain the spring-pressed ratchet member α and the coin-ejecting lever 2 , and the two halves are held together by means of the locking pin 30 Fig. 5 which passes through oppositely disposed holes in the flanges 31 105 of the part t and the hole 32 in the part t' .

Modifications may be made in the general construction of the machine so long as they conform to the claims and to the principles of the operations of the different parts 110 described.

Rubber pads or buffers 33 are provided against which the segments 20 abut to minimize the shocks due to the operations of the machine and the tension of the spring c . 115

I claim:

1. In a coin controlled apparatus, a casing provided with a coin slot, a cylinder comprising separate sections mounted in said casing and provided with a coin slot between 120 said sections adapted to normally register with the coin slot in the casing, a member having notches therein, and a yielding element disposed within the coin slot and normally engaging the notches in said member 125 for locking the cylinder against rotation.

2. In a coin controlled apparatus, a casing having a coin slot therein, a rotatable cylinder disposed within said casing and having a coin slot therein disposed normally 130

- in registration with the coin slot in said casing, a lever disposed within the coin slot of the cylinder for limiting the movement of a coin therein, a notched member, and a 5 spring pressed element engaging said notched member for holding the cylinder against rotation, and a portion of said spring pressed member being disposed within the slot in the path of said coin, whereby 10 upon the insertion of a coin in the slot the spring pressed element will be moved from engagement with the notched member permitting the rotation of said cylinder.
3. In a coin controlled apparatus, a casing having a coin slot therein, a cylinder disposed adjacent said coin slot in the casing said cylinder comprising two sections having a coin slot disposed therebetween, a lever disposed within said coin slot of the cylinder 15 for limiting the movement of a coin therein, said cylinder further having a recess provided therein, a spring pressed element disposed within said recess, a notched member arranged for engagement with the spring 20 pressed element whereby the cylinder will be locked against movement, and a portion of said element being disposed within the slot in the cylinder in the path of a coin, whereby upon the insertion of a coin in said 25 coin slot, the spring pressed element will be disengaged from the notches in said notched member.
4. In a coin controlled apparatus, the combination of a casing having a coin slot therein, of a rotatable cylinder disposed within the casing and having a coin slot formed therein for normally registering with the coin slot in said casing, a movable lever disposed within said cylinder for limiting the 30 movement of a coin within the coin slot of said cylinder, said cylinder having a recess provided therein and opening into the coin slot, a locking element disposed within said recess and having a portion thereof projecting 35 into the coin slot, a notched member designed to receive one end of the locking element for holding said cylinder against rotation, and a spring disposed within the recess for normally and yieldingly holding 40 the locking element in engagement with said notched member.
5. In a coin controlled apparatus, a casing having a coin slot provided therein, a rotatable cylinder including two detachable 45 sections spaced apart and forming a coin 50 slot mounted in said casing with its coin slot normally in registration with the coin slot of the casing, a movable lever projecting into the coin slot of the cylinder for limiting the movement of a coin therein, said cylinder having a recess in one section thereof of opening into the coin slot therein, a locking element disposed within said recess, a portion of the same projecting into the coin slot of the cylinder, a spring disposed in said recess and normally forcing the locking element in a predetermined direction, a circular member disposed at one end of the coin slot and having notches formed therein for receiving a portion of the locking element, 60 and means for supporting said cylinder.
6. In a coin controlled apparatus, a casing provided with a coin slot, a rotatable cylinder journaled in the casing and provided with a coin slot adapted to normally 65 register with the first named slot, a notched member disposed adjacent the cylinder, a spring pressed element carried by the cylinder adapted to normally engage said notched member to lock the cylinder against rotation, 70 a cam operated lever mounted in the slot of the cylinder for the support of a coin in engagement with said spring pressed element, said lever operating at a predetermined time to eject the coin from the cylinder, and a 75 receptacle to receive the ejected coin.
7. In a coin controlled apparatus, a casing provided with a coin slot, a cylinder rotatably mounted in the casing and provided with a coin slot adapted to normally register 80 with the slot in the casing, a notched member disposed adjacent the cylinder, a spring pressed element carried by the cylinder for engagement with said notched member to lock the cylinder against rotation, 85 a lever mounted in the slot of said cylinder for the support of a coin in engagement with said spring pressed member, means for rotating the cylinder, said lever being adapted to eject the coin from the cylinder at a predetermined time, a coin receptacle and a coin chute disposed between said cylinder and said receptacle.

In testimony whereof I have signed this specification in the presence of two subscribing witnesses, this 30th day of April 1912.

FREDERICK WILKINSON.
